(57) **CLAIM**

The ornamental design for a glove, as shown and described.

DESCRIPTION

FIG. 1 is a front perspective view of a glove, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom plan view thereof.

The short-dashed lines on the glove represent stitching that forms no part of the claimed design. The long-dashed broken lines illustrate portions of the glove that form no part of the claimed design.

1 Claim, 7 Drawing Sheets
